INVENTOR.

Harry M. Stegeman

BY James N. Ramsey

ATTORNEY.

UNITED STATES PATENT OFFICE

HARRY M. STEGEMAN, OF FORT THOMAS, KENTUCKY, ASSIGNOR TO THE WADSWORTH WATCH CASE COMPANY, OF DAYTON, KENTUCKY, A CORPORATION OF KENTUCKY

WRISTBAND

Application filed December 5, 1927. Serial No. 237,797.

My invention relates to wrist bands preferably made of metal and includes the fastening means therefor. Reference is made to the pending application of Arthur W. Wadsworth, Serial No. 204,374, filed July 8, 1927.

The object of my invention is to provide means whereby the surfaces of the band sections are prevented from being marred or scratched by the sliding of one end portion 10 over the other or by the cam locking mechanism.

A still further object of my invention is to provide metal band sections of thin metal, the edges of which are increased in thickness, 15 thereby giving the band a thicker appearance than it actually has throughout its cross-sectional area.

Further objects and advantages will become apparent as the description proceeds.

20 The invention consists in the construction, combination, location and arrangement of parts, as hereinafter more fully set forth and claimed.

In the drawing:

25 Fig. 1 is an edge elevation of a metal wrist band in open or expanded position and shown attached to a watch case, the dotted lines representing the locking device in closed position;

30 Fig. 2 is a front view of the metal wrist band showing the clamping means in closed or locked position;

35 Fig. 3 is a longitudinal section of the wrist band and fastening means (the latter being shown in open or unlocked position) taken on line 3—3 of Fig. 2;

Fig. 4 is a similar view but showing the fastening means in closed or locked position;

Fig. 5 is a cross-sectional view taken on the line 5—5 of Fig. 2;

Fig. 6 is a cross-section of one of the metal bands taken on the line 6—6 of Fig. 1;

Fig. 7 is a perspective view of the locking cam;

45 Fig. 8 is a perspective view of the loop formed integral with one end of one of the band sections; and

Fig. 9 is a perspective view of the U-shaped guide.

50 In the embodiment of my invention, as

illustrated, and which shows a preferred construction, I provide a watch case 1 of the usual construction, the ends 2 and 3 of which are provided with lugs 4 which receive the usual spring pin bars 5. The metal band sections 6 and 7 are provided at one end with loops 8, which loops are adapted to receive said bars 5 and in this way said strap sections are removably attached to said watch case 1.

55 End 9 of metal band section 6 is provided with a loop guide 10, as shown in Fig. 1, which is secured to said end 9 in any suitable manner, as for example, by rivets 11.

60 The loop guide 10 is preferably rectangular in shape and wide enough to form opening 12 between end 9 and part 13 of guide 10, which opening is for the purpose of slidably receiving the metal band section 7, as clearly explained under "operation."

65 End 14 of metal band section 7 terminates in elongated loop 15, as clearly shown in Fig. 8. Cam adjusting lever 16 is pivotally supported by pin 17 which pin is received by holes 18 in said lever 16 and elongated opening 19 within loop 15. Guide 20 is substantially U-shaped, as shown in Fig. 5, the ears 21 of which are provided with holes 22 for receiving the ends of pin 17.

70 In order to permanently assemble said guide 20 cam lever 16, elongated loop 15 and pin 17 together (as shown in Fig. 5) I propose to flatten or burnish the ends of said pin 17, so as to form enlarged heads 23. Guide 20 is spaced apart from end 14 of band section 7 to form opening 24 for the purpose of slidably receiving band section 6. The longitudinal edges 25 of band sections 6 and 7 are of a greater thickness than the central part 26, including ornamental portions 26', 75 as clearly shown in Figs. 5, 6 and 8, respectively.

80 Operation.—The operation of my device is as follows:

85 Assume that the band sections 6 and 7, respectively, have been attached to watch case 1, and that band section 6 has been inserted within opening 24 beneath guide 20 and band section 7 has been inserted within opening 12 beneath guide 10 and cam adjust- 90 95 100

ing lever 16 is in the open or unlocked position with the guide 10 near guide 20, as shown in Fig. 1. The bands may then be placed over the hand and upon the wearer's wrist, due to enlarged or expanded opening 27 formed by said band sections 6 and 7 when in the extended position, as shown in Figs. 1 and 2, respectively.

The next step is to slide band section 7 upon band section 6, thereby reducing opening 27 until said bands snugly fit the wrist of the wearer.

The next step is to securely hold or lock said band sections in fixed relation with each other in said adjusted position which is easily accomplished by depressing the cam adjusting lever 16 from the unlocked position, shown by full lines in Fig. 1, to the holding or locked position, shown by dotted lines in Fig. 1. This causes the eccentric portion 28 of cam adjusting lever 16 to bear against the faces 29 of longitudinal raised or thick margins 25, as clearly shown in Figs. 4 and 5, respectively, thereby tightly wedging said band section 7 between said eccentric portions 28 and band section 6, the latter band section being, in turn, wedged against guide 20, as clearly shown in Fig. 5.

It will readily be seen by this construction that the eccentric portions 28 of cam adjusting lever 16 come into contact with the faces 29 only, which prevents said eccentric portions from marring or scratching the central part 26 of band sections 6 or 7. As clearly shown in Fig. 5, the only portions of band sections 6 and 7 touching one another when sliding one upon the other are the raised faces 29. This also prevents marring or scratching of the central plain or ornamental parts 26 when sliding one band upon the other when adjusting said sections about the wrist or removing them therefrom.

Another advantage of this construction is the elongated loop 15. The length of this loop plays an important part when the cam adjusting lever 16 is in the unlocked position, due to the fact that it allows play between the end 14 of band section 7 and end 9 of band section 6, which is desirable for the easy sliding of one band section upon the other when making adjustments and also prevents excessive rubbing of the faces 29.

It will be understood that certain changes and modifications of the invention can be made without departing from the scope or spirit thereof as defined in the claims.

What I claim as new and desire to secure by Letters Patent is:

1. A metal wrist watch band comprising a pair of band sections each having outer exposed raised margins at all times, locking means carried by one end of one section and adapted to engage a raised margin of said section, and means for slidably retaining said

sections in partly overlapped relation with each other at all times.

2. A metal wrist watch band comprising two sections slidably held in partly overlapped relation with each other, raised portions adjacent the side edges of each section and locking means adapted to have a wedging action against said raised portions only whereby said sections are held in adjusted relation to each other, for the purposes specified.

3. A metal wrist watch band comprising a pair of band sections each having outer raised margins, the end portions of which sections are adapted to overlap one another, a guide at the end of one section for receiving the overlapped end of the other section, a U-shaped guide adapted to embrace the raised margins of the overlapped ends, a pin mounted in said guide and a lever having spaced apart cams thereon mounted on said pin and adapted to clamp said overlapped ends in adjustably fixed relation to each other between said cams and U-shaped guide.

4. A metal wrist watch band comprising a pair of band sections each having raised outer exposed margins, the end portions of which sections are adapted to overlap each other, means for slidably retaining said sections in partly overlapped relation with each other, and a lever pivotally attached to one of said band sections and having spaced apart cams thereon adapted to have a wedging action against the raised margins only of said section and to clamp said section against the raised margins of the other section and to prevent marring of said sections during longitudinal movement thereof relative to each other.

5. A metal wrist watch band comprising two sections slidably held in partly overlapped adjusted relation with each other, thickened raised longitudinal margins on each section, and means having a wedging action against said raised margins whereby said sections are held in adjusted relation to each other without scratching or otherwise marring the portions of the sections intermediate the thick raised longitudinal margins, substantially as set forth and for the purposes specified.

HARRY M. STEGEMAN.
